ABSTRACT OF THE DISCLOSURE

A printing mechanism including an ordinal series of digital printing wheels is set to selected digital positions by an electric control circuit including an ordinal series of digital sets of manually operated key switches. After actuation of a key switch for each printing wheel, a start switch is operated whereupon the printing wheels are automatically set to the selected printing position. The mechanism is built into a cavity of a printing cylinder so that a copy sheet imprinted by the same is also imprinted by the printing wheels. It is also possible to arrange the printing wheels in the path of movement of a copy sheet imprinted in a printing machine, and to use the printing wheels to print additional information on the copy sheet.

BACKGROUND OF THE INVENTION

Printing devices including a plurality of printing wheels requiring manual setting are known. Particularly, it is known to mount a series of printing wheels in a cavity of a printing cylinder or duplicating roller so that after manual setting of the printing wheels, additional information is imprinted on a copy sheet which is also imprinted by a master attached to the duplicating cylinder. The manual setting of each printing wheel is generally carried out by an implement for engaging recesses of a toothed segment secured to each printing wheel, and to turn the segment with the printing wheel until the implement is stopped by a stationary stop. The manual setting of a printing mechanism having a great number of printing wheels leads to errors and is very time consuming.

SUMMARY OF THE INVENTION

It is one object of the invention to overcome the disadvantages of known printing devices including a series of independently settable printing wheels, and to provide a key controlled motor driven setting apparatus for a series of printing wheels.

Another object of the invention is to provide a key controlled setting apparatus for printing wheels which is so compact that it can be mounted in a cavity of a printing cylinder.

Another object of the invention is to provide a key controlled automatic setting apparatus for printing wheels which can be mounted on the support of a printing or duplicating machine in such a position that the printing wheels print on copy sheets imprinted in the machine and transported away from the printing cylinder.

Another object of the invention is to provide a key controlled automatic setting apparatus by which ordinal printing wheels are set to selected digital positions respectively.

Another object of the invention is to provide a key controlled automatic setting apparatus which accurately and reliably sets printing wheels to printing positions selected by operation of the respective keys.

In accordance with the invention, each printing position of each printing wheel is correlated with a key operated selector switch, and each printing wheel is associated with coupling means which are operated by elec-

2

tromagnetic means under the control of a cam operated interrogation device to couple the printing wheels to drive means in angular position corresponding to the selected digit or character representing types on the same.

5 One embodiment of the invention comprises a series of printing wheels, each having a set of types, and being turnable between a set of printing position, a series of coupling means for connecting drive means with the printing wheels, respectively; a set of cam means rotated by the drive means; and a control circuit.

In accordance with the invention, the control circuit includes a series of electromagnetic means for operating the coupling means, respectively, a series of sets of key switches, and a set of interrogation switches sequentially actuated by said cam means during one revolution of the same, and connected with said key switches, respectively.

The several series all have the same number, and the several sets also have the same number. Specifically, if only numbers are to be printed, each series in an ordinal series, and each set is a digital set for representing the ten digits 0 to 9. However, the apparatus can be used for printing words, so that each printing wheel has types respectively corresponding to an alpha numerical font.

In one embodiment, the drive means include a shaft 25 supporting the printing wheels for free rotation, and the coupling means are biased to connect the shaft with the printing wheels, and are operable by the electromagnetic means to disengage the printing wheels and to engage the same in selected angular positions.

30 It is advantageous to drive the shaft from a motor by means of a Geneva transmission so that the shaft, and printing wheels coupled with the same, turn stepwise so that the printing types of each printing wheel move stepwise to a printing line. The motor is started by a start switch, and after one revolution of the shaft, a switch is actuated by a projection on the shaft to stop the motor, shaft, and printing wheels.

It is advantageous to arrest all printing wheels in a position in which the types thereon are accurately aligned 40 in axial direction. The arresting means is operated by another electromagnetic to release the printing wheels when the start switch is operated, and to engage the same again when the printing wheels have been set.

When the printing wheels are mounted on a drive shaft, 45 the coupling means preferably include a set of coupling teeth on the drive shaft, and a biased coupling pawl normally engaging the coupling teeth, and being operable by a control lever of the electromagnetic means to release the coupling teeth to permit relative movement between 50 the printing wheels and the drive shaft. The electromagnetic means can be simultaneously energized for causing disengagement of all coupling means.

The set of cam means is mounted on the drive shaft and rotate with the same to sequentially actuate the interrogation 55 switches which are connected with all key switches, each set of key switches being connected in series with the respective electromagnetic means and with manually opened and closed contacts. All electromagnetic means are simultaneously energized by the closed contacts, and 60 are successively de-energized by the interrogation switches at moments depending on the selection of key switches. When the respective electromagnetic means is de-energized in a particular selected angular position of the drive shaft, a respective coupling means again assumes a coupling position, and more specifically, the coupling pawls engage the coupling teeth of the drive shaft.

In order to set the printing wheels in selected angular 65 positions on the shaft, the coupling pawl transports the printing wheel only during a part of the net yet completed revolution of the shaft so that the selected type stops in the printing line.

While the above described embodiment is preferably mounted in a cavity of a printing cylinder, another embodiment of the invention is disposed following the printing line of a printing cylinder, such as a duplicating roller, and the printing wheels print on copy sheets already imprinted by the master on the duplicating roller, and being transported away from the same. In this embodiment, the printing wheels are mounted for free rotation on a shaft, but are not driven by the same. The shaft is carried by a movable support which is operated by a printing magnet to move the support with the printing wheels to a position for printing on the copy sheet.

The transporting means of the copy sheets permit stopping of the same while being imprinted by the printing wheels. After the printing operation, an electromagnet is energized to withdraw the stop means from the path of the imprinted copy sheet, and the transporting means are again effective to discharge the same. The discharged copy sheet operates a switch which de-energizes the respective magnet so that the stop means becomes again operative to stop the next following copy sheet.

In this embodiment, the drive means include a motor driven shaft carrying the cam means and being connected by gears to a drive cam which operates cam follower means. Each coupling means includes a first coupling member having a rack portion meshing with a gear secured to the respective printing wheel, and a ratchet portion. A biased second coupling member in the form of a coupling pawl is reciprocated by the cam follower means and is biased to engage a coupling recess in the respective first coupling member. Each coupling means also includes an arresting member engaging the ratchet portion of the first coupling member, and being operated by an electromagnetic means.

The cam shaft by which the interrogation switches are sequentially operated, is driven by a motor through a one revolution clutch so that the cam shaft, and also the drive cam stop after one revolution of the cam shaft.

The rack portions of the first coupling members turn all printing wheels one revolution so that all types traverse the printing line.

The interrogation switches cause de-energization of the electromagnets controlling the arresting means so that the latter engage the first coupling member and arrest the same in a position in which the respective printing wheel is in a printing position selected by operation of the respective key switch.

It is advantageous to provide a switch which is opened by the drive means to energize the respective electromagnet to operate the arresting means to release the first coupling member. This switch is opened again before the respective interrogation switch closes again after being opened by the respective cam means.

The drive cam causes return of all coupling members to an initial position during a second revolution performed by the cam shaft upon a second actuation of the one revolution clutch.

The novel features which are considered as characteristic for the invention are set forth in particular in the appended claims. The invention itself, however, both as to its construction and its method of operation, together with additional objects and advantages thereof, will be best understood from the following description of specific embodiments when read in connection with the accompanying drawings.

BRIEF DESCRIPTION OF THE DRAWING

FIG. 1 is a fragmentary plan view illustrating one embodiment of the invention which is mounted in a cavity of a duplicating cylinder;

FIG. 2 is a fragmentary sectional view taken on the line A-B in FIG. 1 and illustrating a part of the apparatus on an enlarged scale;

FIG. 3 is a fragmentary sectional view taken on line 75

C-D in FIG. 1, and illustrating another part of the apparatus on an enlarged scale;

FIG. 4 is a diagram illustrating the electric control circuit of the embodiment of FIGS. 1 to 3;

FIG. 5 is a fragmentary schematic elevation illustrating a second embodiment of the invention disposed adjacent the printing roller of a duplicating machine for printing on discharged imprinted copy sheets; and

FIG. 6 is a diagram illustrating the electric control circuit of the embodiment of FIG. 5.

DESCRIPTION OF THE PREFERRED EMBODIMENTS

Referring first to the embodiment of FIGS. 1 to 4 in which the setting apparatus is mounted in a cavity of a printing cylinder or duplicating roller 1 which carries a master 128 on its periphery, printing cylinder 1 is mounted for turning movement on shaft 55, and cooperates with a counterpressure roller, not shown, to imprint on a copy sheet the text of master 128. An indexable drive shaft 30 is mounted in the side walls of the cavity for rotation, and is driven from a motor 31 through a Geneva transmission, see FIG. 3, including a rotary driving member 37 provided with a pin 38 which cooperates with the recessed driven wheel 39 to rotate shaft 30 stepwise in the direction of the arrow F. The blocking member 40 turns with the driving member 37 and blocks turning movement of the driven member 39 intermediate its angular steps until transporting pin 38 engages the respective next following recess 41 of the driven member 39.

An ordinal series of printing wheels 28 is mounted on shaft 30, each wheel having a digital set of printing types. A coupling pawl 27 is mounted on each printing wheel 28 for pivotal movement about a pin 29, and is biased by a spring 44 to engage one of the notches between coupling teeth on shaft 30. The number of coupling teeth and notches is the same as the number of types on each printing wheel 28. Preferably, ten types are provided which respectively represent the digits from 0 to 9. The types are separated by arresting notches 36 which can be axially aligned, irrespective of the digital printing position of each printing wheel 28. One printing type projects out of the cavity and is in a printing position in which the type thereon can be printed on a copy sheet together with the text of the master 128 during rotation of printing cylinder 1.

On a shaft 33 mounted in the side walls of the cavity, a U-shaped arresting means is mounted for turning movement, and has an arresting bar 34 which is normally urged by a spring 35 to a position engaging a row of notches 36 so as to align the printing wheels 28. Upon operation of an electromagnet 32, arresting bar 34 is withdrawn from the notches 36 of the printing wheels 28 so that the same can be turned and set to desired printing positions.

Two rows of electromagnetic control means 20 are respectively mounted on axially extending supporting brackets 18 and 19 whose angular end portions are secured to the side walls of the cavity. Electromagnets 20 respectively operate control levers 21 and 22 which are mounted on pivots 24 and 23 and are biased by springs 25 and 26 which are secured to fixed points 129 and 47 and urge control levers 22, 21 to the inoperative positions shown in FIG. 2. Upon energization of the electromagnetic control means 20, the axially alternating control levers 21 and 22 are selectively moved to pawl 27 of the same order, and to release the coupling between pawl 27 and the teeth of drive shaft 40 until electromagnetic means 20 are again de-energized.

As explained above, shaft 30 can be stepwise turned by the Geneva transmission 37 to 40 while some or all printing wheels 28 are uncoupled from the same and locked by the arresting bar 34.

A digital set of staggered cam means 42 is secured to shaft 30 and turns stepwise with the same. Each cam

means 42 is correlated with one of the digits from 0 to 9, and cooperates with a corresponding digital interrogation switch 43, shown in FIG. 4 so that switches 43 are sequentially opened during each revolution of shaft 30 which takes place in ten steps.

A contact bar 16 is secured to the side walls of the cavity and carries a series of stationary contacts 17 arranged in an axially extending row, as shown in FIGS. 1 and 3. As best seen in FIG. 4, the stationary contacts 15 are respectively connected with the electromagnetic control means 20 which are respectively connected to digital sets of key switches 48 which can be independently operated to select one of the digits from 0 to 9 in each set of ten key switches 48. While keys are shown only for the first and last key switch of each digital set, it will be understood that each key switch can be independently selected and operated. The number of sets of key switches 48 corresponds to the number of electromagnetic means 20, and to the number of printing wheels 28. FIG. 4 shows the arrangement only for three orders, but it will be understood that any number of orders can form the series of printing wheels 28, and that the same number of digital sets of key switches 48 will have to be provided for selection of the desired printing positions of each printing wheel.

In the position illustrated in FIG. 3, an ordinal series of contacts 15 cooperates with the ordinal series of contacts 17. The contacts 15 are mounted on a movable contact bridge 7 which is supported for turning movement by pivots 13 on lateral walls 11 and 12, as best seen in FIG. 1. One leg of the U-shaped contact bridge 7 carries a pin 8 engaged by an angular lever 3 which is mounted on a pivot 2 on lateral wall 11 and is biased by a spring 6 to abut a first stop 9 so that the weight of contact bridge 7 moves the same to the position in which contacts 15 respectively abut contacts 17 for energizing all electromagnetic control means 20 simultaneously. When angular lever 3 is turned in clockwise direction as viewed in FIG. 3 to a position abutting stop 10, spring 6 moves about a fixed holding stud 4 through a dead center position, and angular lever 3 is arrested in the new position in which all contacts 15 are spaced from all contacts 17 so that electromagnetic control means 10 are deenergized.

Referring now to the circuit diagram of FIG. 4, as explained above, an ordinal series of key switches 48 is provided, only three sets of key switches being shown for the sake of simplicity. The ten interrogation switches 43 are respectively connected with the corresponding digital key switches of all sets. One terminal of a voltage source is connected to all movable contacts 17 on contact bar 7 and also to a switch 46 which is operated by an actuator pin 45 on shaft 30, as shown in FIG. 3. A relay winding 50 is connected in series with switch 46 and controls three relay switches 51, 52, 53 which are respectively connected with the other terminal of the voltage source, which is also connected with the interrogation switches 43.

A start switch 49 is connected in series with relay winding 50 and in parallel with the holding contact 51 of the same. The second relay contact 52 is connected in series with the electromagnet 32 by which the arresting means 34 is operated, as shown in FIG. 2. The third relay contact 53 is connected in series with motor 31, see FIG. 3, by which shaft 30 is stepwise rotated by means of the Geneva transmission 37 to 40 together with the digital set of cam means 42 by which the interrogation switches 43, not shown in FIG. 1, are sequentially operated during each revolution of cam 30. A delay device 54 is connected in series with motor 31 so that when relay 50 operates relay contacts 52 and 53, electromagnet 32 first operates arresting means 34 to release the printing wheels 28, whereupon rotation of shaft 30 by motor 31 is started.

When printing cylinder 1 is in its normal initial posi-

tion, the manually operated angular lever 3 is turned from a position abutting stop 10 to the position illustrated in FIG. 3 abutting stop 9 so that all ordinal contacts 17 engage the respective stationary contacts 15, and the apparatus is ready for the selection of the new digits to which each ordinal printing wheel 28 is to be set. One key switch 48 of each digital set is actuated by the operator, and closed. Evidently, the keys of the key switches of each set are provided with indicia indicating the digits from 0 to 9, and as many sets of keys are provided as there are printing wheels. For example, forty printing wheels 28, and a corresponding number of sets of key switches 48, electromagnetic means 20, and contacts 15 and 17 may be provided.

Each electromagnetic means 20 is energized through a selected key switch 48 and an interrogation switch 43 closed by a cam 42 to operate the control levers 21 and 22 in the direction of the arrow E in FIG. 2 so that the coupling pawls 27 are turned by control levers 21 and 22 to a position disengaging the coupling teeth of shaft 30 and interrupting the coupling connection between the same and printing wheels 28.

The start switch 49 is now operated, relay 50 is energized through the closed switch 46, and relay contacts 51, 52, 53 close. Holding contact 51 bridges start switch 49 so that the same can be released by the operator. Relay contact 52 effects energization of electromagnet 32 which withdraws arresting means 34 from all printing wheels 28. After a delay caused by delay device 54, motor 31, which is a quickly stopping brake motor, is energized and stepwise drives shaft 30 through the Geneva transmission 37 to 40 so that the ten cam means 42 sequentially open the interrogation switches 43 whereby electromagnetic means 20 are sequentially de-energized and permit springs 25, 26 to sequentially turn control levers 21 and 22 to positions releasing the biased coupling pawls 27 which immediately couple the respective correlated printing wheels with shaft 30. Therefore, the angular position of each coupled printing wheel 28 on shaft 30 will depend on the selection of the respective key switch 48 so that a line of types representing the digits selected by key switches 48 is formed. At the end of one revolution of shaft 30, the selected types representing the selected number will be in a printing position projecting from the periphery of the printing cylinder.

The rotation of shaft 30 is terminated after one revolution when the projecting actuator pin 45 on shaft 30, see FIG. 3, engages stop switch 46 and shortly opens the same so that relay 50 is de-energized, and holding contacts 51, 52, 53 open. Electromagnet 32 is de-energized, and permits springs 35 to move arresting means 34 to the operative position shown in FIG. 2 whereby each printing wheel is arrested in the selected digital printing position, while at the same time types located in the same axial line are accurately aligned. Brake motor 31 quickly stops so that shaft 30 with the printing wheels 28 coupled to the same is also stopped. Contact bridge 7 can now be turned by operation of angular lever 3 to a position in which contacts 15 and 17 are spaced so that electromagnetic means 20 are all de-energized.

A printing operation on a copy sheet can now be started. Printing cylinder 1 is rotated so that a copy sheet transported by the printing cylinder and by a counterpressure roller, not shown, is imprinted not only by the text of the master 128, but also by the selected series of types which are aligned in axial direction.

While the printing wheels 28 have been described to have ten digital positions, and ten printing types representing the digits from 0 to 9, it is apparent that any alpha numerical character may be used for a type on a printing wheel.

Referring now to the embodiment illustrated in FIGS. 5 and 6, an ordinal set of digital printing wheels 82 is

mounted for rotation on a shaft 132 on a supporting frame 62 which is located outside of the printing cylinder 1.

A copy sheet 57 printed by the master 128 on printing cylinder 1 during rotation about shaft 55, is transported by pairs of transporting rollers 58, 59 along a supporting table 66. Transporting rollers 59 are continuously rotated by drive means, not shown. Transporting rollers 58 and 59 have shafts 63 and 64, shafts 63 being mounted for vertical movement with transporting rollers 58 in slots 60 in the lateral walls of the supporting frame 62. Springs 55 connect shafts 63 and 64 to urge the rollers to a position engaging and transporting copy sheet 57 along table 66 until the leading edge of copy sheet 57 abuts the end portion of an angular stop lever 67 which is mounted for turning movement on a shaft 71 and holds the copy sheet in the illustrated position. A spring 69 urges the armature 70 of an electromagnet 68 to a position in which stop lever 67 is operative, but when electromagnet 68 is energized, stop lever 67 is withdrawn to an inoperative position, and copy sheet 57 can be further transported by the transporting rollers 58, 59.

In the stop position of the copy sheet 57, a switch 74 is closed. Switch 74 controls an inking magnet 75 which, when energized, turns in the direction of the arrow H so that an inking means 80 including a roller passes over the printing types which are aligned in a row located opposite copy sheet 57. Inking lever 80 is mounted for turning movement on a support 79 which also carries the shaft 132 of printing wheels 82. When inking lever 80 has been displaced to the angular position shown in chain lines in FIG. 5, it operates a switch 83 by which printing magnet 85 is energized.

Support 79 is pivotally connected with a forked armature portion 90 of printing magnet 85 and is biased by spring 89 to turn about support shaft 78 to the illustrated position in which the printing wheels 82 are spaced from the copy sheet. When printing magnet 85 is energized, support 79 turns about shaft 78 to a printing position in which the lowermost axial row of printing types engages copy sheet 57.

An indexable drive shaft 104 is driven through a one-revolution clutch, not shown, by a motor, not shown, and carries a digital set of cams 110 which are angularly staggered and axially spaced to sequentially engage a digital set of axially spaced interrogation switches 111, see also FIG. 6.

A gear 100 on shaft 104 meshes with a gear 101 secured to a shaft 102 which carries a drive cam 103 whose periphery has two parts symmetrical to one plane of symmetry. Shaft 102 has a projecting cam portion and a recessed portion for operating a switch 105 which is connected in series with the interrogation switches 111, as shown in FIG. 6. A cam follower lever 115 cooperates with cam 103 toward which it is biased by spring 116, and is mounted on a shaft 114 for angular reciprocating movement. The free end of cam follower lever 115 has a slot in which a pin 117 secured to a link means 120 is mounted. Link means 120 carries a prismatic body 121 having vertical slots receiving the ends of elongated coupling members 112. Body 121 and link 120 are guided by rollers 118 for straight reciprocating movement along a supporting surface 119.

Coupling pawls 123 are mounted in the vertical slots of body 121 for turning movement about the pivot 122 and are biased by springs 124 to engage the upper notched edges of correlated coupling members 112 which are formed with recesses engaged by coupling pawls 123 in the illustrated position.

Each coupling member 112 has an end portion with a lower edge formed as a rack meshing with a correlated pinion 125 secured to one of the printing wheels 82. A coupling member 112 with a rack is provided for each printing wheel 82 of the series so that each printing wheel 82 can be set to a selected angular position, as will be described hereinafter. Each coupling member 112 co-

operates with a coupling pawl 123, an ordinal series of coupling pawls 123 being mounted in the body 121.

An ordinal series of electromagnetic control means 106 is mounted on the top plate of support 79 and each electromagnetic control means 20 has a fork-shaped link pivotally connected with an arresting pawl means 108 which is turnable on a shaft 109 mounted on support 79. Springs 113 act on the armatures of electromagnetic control means 106 and urge the same to a position in which arresting pawl means 108 engage notches in the upper edge of the end portion of the respective coupling member 112. Ten notches are provided, corresponding to ten digital positions of the respective printing wheel 82. A switch 92 is operated by support 79 and is closed in the printing position of the printing wheels 82, and opened in the illustrated position.

Referring now to FIG. 6, one terminal of a voltage source is connected to all electromagnetic control means 106, which correspond to the electromagnetic control means 20 of the embodiment of FIGS. 1 to 4. Each electromagnetic control means is connected to a digital set of key switches 98, and the number of sets of key switches is the same as the number of printing wheels. Ten interrogation switches 111 are respectively connected with the corresponding key switches of all ordinal sets of key switches 98.

The other terminal of the voltage source is connected by switch 105 to the interrogation switches 111.

The inking electromagnet 75 is connected in series with the RC network 76, 77 and the switch 74 which is closed by a copy sheet 57 in the stopped position shown in FIG. 5. The printing magnet 85, which operates support 79 of the printing wheels 82, is connected in series with a delay device and a RC network 86, 87, and also with a switch 83 which is operated by the inking means 80 after the same has inked the row of types of the printing wheels which is located in the printing position opposite the copy sheet 57. Another switch 97, shown at the right of FIG. 5, is also operated by copy sheet 57 when the same have been transported out of the illustrated position after printing. Switch 97 is connected in series with the relay 93 which controls two relay contacts 94 and 95. Switch 92 is also connected in series with relay 93 and switch 97, and is bridged by the holding contact 94 when relay 93 is energized. Relay contact 95 is connected in series with the releasing magnet 68 by which stop lever 67 is moved to a position releasing the leading edge of copy sheet 57 so that the same can move on. Control lever 73 is also connected with the fork-shaped armature portion 70 and is turnable about a shaft 72 to move shaft 63 with the respective transporting roller 58 away from copy sheet 57 so that a copy sheet 57 abutting stop lever 67 is not transported.

During rotation of printing cylinder 1, copy sheets 57 are imprinted by the text on the master 128, stripped off the printing cylinder, and transported by the first pair of transporting rollers 58, 59, and then by the driven transporting roller 59 of the second pair of transporting rollers until its leading edge abuts stop lever 67 in the position illustrated in FIG. 5. Since the upper transporting roller 58 of the second pair is held by lever 73 spaced from the respective lower transporting roller 59, copy sheet 57 is only lightly pushed against stop lever 67, and remains in the illustrated position while closing switch 74.

Switch 74 energizes the turnable inking magnet 75 over RC network 76, 77, so that inking lever 80 is turned to the position shown in chain lines and inks the lowermost row of types of the printing wheels 82 whereupon inking lever 80 closes switch 83. After this movement of inking lever 80 in the direction of the arrow H against the action of spring 81 which is secured to support 79 by a pin 84, spring 81 returns inking lever 80 to its initial position.

Closing of switch 83 by the inking lever 80 effects energizing of printing magnet 85 through RC network 86, 75 and delay device 88 so that printing magnet 85 turns

support 79 about shaft 78 against the action of spring 89 to a printing position in which the lowermost row of type faces engages the copy sheet 57 and prints a line of digits or characters on the same. During the printing operation, switch 92 is closed by support 79 and energizes relay 93 since switch 97 is not yet opened by copy sheet 57 which is held by the stop lever 67 in the illustrated printing position. Relay 93 closes the holding contact 94 so that switch 92 is bridged when support 79 is returned by spring 90 to its initial inoperative position, and relay contact 95 energizes release magnet 68 which turns stop lever 67 to a position releasing the leading edge of copy sheet 57, while control lever 73 permits the spring biassed top roller 58 of the second pair of supporting rollers to move downward into full driving engagement with copy sheet 57 so that the same is transported and gripped by the third pair of transporting rollers 58, 59 until the leading edge of the transported copy sheet opens switch 97. Switch 97 interrupts the circuit of relay 93 so that relay contacts 94 and 95 open again and the release magnet 68 is de-energized, permitting spring 69 to turn stop lever 67 to the operative stop position, and control lever 73 to raise top roller 58 of the second pair of transporting rollers so that the next copy sheet can be received from the first pair of transporting rollers 58, 59.

The setting of the printing wheels 82 to new selected angular positions representing a new number having several orders, each of which is printed by a digital printing wheel 82, is accomplished under the control of drive shaft 104 which is driven from a motor, not shown, through a one-revolution clutch 99 to turn one revolution, when a switch, not shown, is manually operated. Gears 100 and 101 are designed so that drive cam 103 performs half a revolution with shaft cam 102 when drive shaft 104 and cams 110 thereon perform one revolution. Upon the start of the revolution of drive shaft 104, the circumferential cam projection on shaft 102 closes switch 105 which, as best seen in FIG. 6, is connected with all interrogation switches 111 which are sequentially closed by the ten cams 110. All electromagnetic control means 106 are energized through the segmentally closed interrogation switches 111, and through the single key switch 58 selectively closed in each digital set of key switches.

The energized electromagnetic control means 106 overcome springs 113 and turn all arresting means 108 to positions releasing the respective coupling members 112, and thereby the printing wheels 82 which can now be freely turned by the respective coupling members 12.

The first cam 110 is correlated with the digit 0 and opens the respective interrogation switch 111 so that in all orders in which the 0 key switch 98 was selected and actuated, the respective electromagnetic control means 106 are de-energized so that the respective arresting means 108 are urged by the respective springs 113 to engage the respective recess in the respective coupling members 112 whereby the respective printing wheels 82 are locked in a position in which the zero types thereof are located opposite the copy sheet 57, ready for printing a 0 in the respective order.

During this operation, a circular portion of the drive cam 103 cooperates with cam follower lever 115, but after arresting of the respective printing wheels 82 in the zero position, drive cam 103 acts on cam follower means 115, 120 to move body 121 with all coupling pawls 123 in the direction of arrow L.

The arrested coupling members 112 cannot be displaced, and the respective pawls 123 move out of the recesses in the same, and slide along the same during the reciprocating stroke to the right of the cam follower means 115, 120.

The other coupling pawls 121 remain coupled with the respective coupling members 112 and move the same to the right in the direction of the arrow L so that the respective printing wheels 82 are turned due to the engage-

ment of the rack portions of coupling members 112 with the respective pinions 125.

One cam 110 after the other engages and opens the correlated digital interrogation switch 111, so that electromagnetic control means 106 are de-energized by each operated interrogation switch which is connected to a selected and closed key switch 98. Each de-energized electromagnetic control means 106, permits spring 113 to operate arresting means 108 to arrest coupling member 112, and thereby printing wheel 82 associated therewith in an angular position representing the digit selected by operation of the respective key switch 98 in the set of key switches correlated with the respective printing wheel 82. After one revolution of drive shaft 104 with cams 110, all printing wheels 82 are set to selected positions and arrested by arresting means 108 so that a printing operation can be started during which printing magnet 85 presses the lowermost row of types representing the selected number against copy sheet 57.

At the end of one revolution of the drive shaft 104, drive cam 103 has turned half a revolution, and the cam follower means 115, 120 are at the end of the reciprocating stroke to the right. Since the one revolution clutch 99 stops shaft 104 after one revolution, the cam follower means and the body 121 with coupling pawls 103 remain in the same position, while any desired number of copy sheets is imprinted with the respective selected number.

After completion of the printing operation, the one-revolution clutch 99 is again started to rotate shaft 104 one revolution so that drive cam 103 performs the second half of its revolution during which spring 116 turns the cam follower means 115, 120 to perform a reciprocating stroke toward the left, as viewed in FIG. 5. During this movement, all coupling pawls 123 are urged by the respective springs 124 into the coupling recesses in coupling members 112 so that at the end of the reciprocating stroke, all printing wheels 82 are returned to the zero position. Arresting means 108 slides over the tapered backs of the ratchet teeth of coupling members 112 during the reciprocating stroke to the left.

During the second half revolution performed by drive cam 103, switch 105 remains open due to the shape of cam 102 so that the interrogation switches 111 and electromagnetic control means 106 are not energized.

It will be understood that each of the elements described above, or two or more together, may also find a useful application in other types of setting apparatus for printing wheels differing from the types described above.

While the invention has been illustrated and described as embodied in a key controlled setting apparatus for an ordinal series of printing wheels which are individually turnable between digital printing positions, it is not intended to be limited to the details shown, since various modifications and structural changes may be made without departing in any way from the spirit of the present invention.

What is claimed as new and desired to be protected by Letters Patent is set forth in the appended claims.

1. Key controlled setting apparatus for printing wheels, comprising, in combination, a series of printing wheels, each having a set of types, and being turnable between a set of printing positions; drive means including indexable stepwise movable drive shaft means; a series of coupling means for connecting said drive shaft means with said printing wheels, respectively; a set of staggered cam means stepwise moved by said drive shaft means and moving along paths; and a control circuit including a series of electromagnetic means for operating said coupling means, respectively, a series of sets of key switches, and a set of interrogation switches located in said paths, respectively, and being sequentially actuated by said staggered cam means, respectively, during one revolution of said drive shaft means, said interrogation switches being connected with said key switches, respectively, of said sets of

key switches so that when a selected key switch of any set of key switches is actuated, the respective correlated electromagnetic means operates the respective correlated coupling means upon actuation of the respective interrogation switch to couple said drive shaft means with the respective printing wheel so that the same is turned to a printing position corresponding to the selected key switch.

2. Key controlled setting apparatus as claimed in claim 1 in combination with a printing machine having means for transporting a copy sheet along a path, and printing means located in said path for printing on one part of said copy sheet; wherein said printing wheels are located along said path; and comprising means for operating said series of printing wheels to make an imprint on another part of said copy sheet.

3. Key controlled setting apparatus as claimed in claim 2 said printing means comprising a printing cylinder having a cavity in which said printing wheels, coupling means, cam means and electromagnetic means are located.

4. Key controlled setting apparatus as claimed in claim 2 wherein said transporting means transport the copy sheet after said one part has been imprinted by said printing means, said printing machine including supporting means for the transported copy sheet; and wherein said printing wheels are located adjacent said supporting means and operable for printing on said other part of said copy sheet.

5. Key controlled setting apparatus as claimed in claim 1 wherein said drive shaft means support said printing wheels for rotation; said drive means including a motor for driving said drive shaft means; wherein said coupling means connect said drive shaft means with said printing wheels, respectively, and are operable by said electromagnetic means to disengage said printing wheels, respectively, and to engage the same with said drive shaft means in selected angular positions respectively correlated with different types.

6. Key controlled setting apparatus as claimed in claim 5 wherein each of said printing wheels has arresting recesses between said types; comprising an arresting means movable to and from an arresting position engaging said recesses and aligning the same and said types while blocking rotation of said printing wheels; comprising another electro-magnet for operating said arresting means; and means for energizing and de-energizing said other electromagnet and said motor so that said arresting means releases said printing wheels before said motor rotates the same, and moves to said arresting position when said motor has stopped so that said printing wheels remain in selected printing positions aligned for printing.

7. Key controlled setting apparatus as claimed in claim 1 wherein said drive means include drive cam means rotated by said drive shaft means, and cam follower means cooperating with said drive cam means; and wherein each coupling means includes a first coupling member connected with the respective printing wheel for movement between said printing positions, a second coupling member disengagably coupled with said first coupling member and moved by said cam follower means and arresting means operated by said electromagnetic means to block movement of said first coupling member in selected digital positions so that said second coupling member is disengaged from said first blocked coupling member while moving with said cam follower means.

8. Key controlled setting apparatus as claimed in claim 1 in combination with a printing cylinder having a cavity in which said printing wheels, coupling means, cam means, and electromagnetic means are located; wherein said drive shaft means is mounted in said cavity supporting said printing wheels for rotation, and being coupled with the same by said coupling means, a motor mounted in said cavity, and a Geneva transmission connecting said motor with said drive shaft means so that the same is turned stepwise between digital positions and transmits stepwise movement to said coupling means and

said printing wheels so that the same turn between said printing positions.

9. Key controlled setting apparatus as claimed in claim 1 wherein said drive means include a motor driving said drive shaft means; and wherein said control circuit includes switch means controlling said motor and operated by said drive shaft means after one revolution for terminating rotation of said motor and drive shaft means so that the types corresponding to the selected key switches are aligned in a printing line at the end of one revolution.

10. Key controlled setting apparatus as claimed in claim 1 in combination with a printing machine having means for printing copy sheets; and comprising transporting means for transporting an imprinted copy sheet along a path; a supporting surface for said copy sheet along said path; a shaft supporting said printing wheels for rotation; a movable support for said shaft and the printing wheels thereon; and printing magnet means for moving said support toward and away from said supporting surface and between a printing position in which said printing wheels print on said imprinted copy sheet, and an inoperative position in which said printing wheels can be set to selected printing positions.

11. Key control setting apparatus as claimed in claim 10 comprising transporting means having a transporting position for positively transporting said copy sheet, and an engaging position for frictionally engaging said copy sheet; stop means having a stop position for stopping said copy sheet and a releasing position releasing the same; and operating means for moving said transporting means and stop means simultaneously to said transporting and releasing positions, and to said engaging and stop positions respectively.

12. Key control setting apparatus as claimed in claim 11 wherein said operating means include an electromagnet having a spring biassed armature for urging said transporting means and stop means to said engaging and stop positions, respectively and being energizable for moving the same to said transporting and releasing positions; and wherein said control circuit includes switch means operated by said copy sheet to energize and de-energize said electromagnet.

13. Key control setting apparatus as claimed in claim 10 comprising inking means for said printing wheels; inking magnet means for moving said inking means to and from an inking position; and wherein said control circuit includes an inking switch operated by said transported copy sheet and connected with said inking magnet for energizing the same.

14. Key control setting apparatus as claimed in claim 13 wherein said control circuit includes a printing switch connected with said printing magnet means and operated by said inking means after movement to said inking position to energize said printing magnet means so that the inked printing wheels print on said copy sheet.

15. Key control setting apparatus as claimed in claim 10 wherein said drive shaft means includes a rotary shaft having a projecting portion; and wherein said control circuit includes a switch operated by said projecting portion to energize and de-energize said electromagnetic means, and connected in series with said interrogation switches and key switches.

16. Key control setting apparatus as claimed in claim 10 wherein said drive means include a one revolution clutch for rotating said drive shaft means and cam means one revolution, drive cam means rotated by said one revolution clutch, and cam follower means operating said coupling means for turning and setting said printing wheels.

17. Key control setting apparatus as claimed in claim 16 wherein each coupling means includes a coupling member connected with the respective printing wheel and having a digital set of arresting recesses; wherein said coupling means comprise spring biassed arresting means

for engaging said arresting recesses, and respectively operated by said electromagnetic means to release said arresting recesses when said electromagnetic means are energized, so that said printing wheels are arrested in selected printing positions when said electromagnetic means are sequentially de-energized by said interrogating switches under the control of said cam means.

18. Key control setting apparatus as claimed in claim 17 wherein said drive shaft means include a rotary shaft having a projecting portion; wherein said control circuit includes a switch operated by said projecting portion to energize and de-energize said electromagnetic means and connected in series with said interrogation switches; and wherein said switch is closed before said interrogation switches are opened by said cam means, and again opened before said interrogation switches are again closed by said cam means.

19. Key control setting apparatus as claimed in claim 16 wherein said drive means include means for rotating said drive cam means at half the speed of said one revolution clutch; and wherein said cam follower means move in a working stroke in one direction for setting said printing wheels during half a revolution of said drive cam means, and in a return stroke during the second half revolution of the same for clearing said printing wheels; and wherein said one revolution clutch is once started for setting said printing wheels, and a second time started for clearing said printing wheels.

20. Key controlled setting apparatus for printing wheels, comprising, in combination, a series of printing wheels, each having a set of types, and being turnable between a set of printing positions; drive means including drive shaft means, drive cam means rotated by said drive shaft means, and cam follower means cooperating with said drive cam means; a series of coupling means for connecting said drive means with said printing wheels, respectively; a set of cam means rotated by said drive means; and a control circuit including a series of electromagnetic means for operating said coupling means, respectively, a series of sets of key switches, and a set of interrogation switches sequentially actuated by said cam means, respectively, during one revolution of said set of cam means and connected with said key switches, respectively, of said sets of key switches so that when a selected key switch of any set of key switches is actuated, the respective correlated electromagnetic means operates the respective correlated coupling means upon actuation of the respective interrogation switch to couple said drive means with the respective printing wheel so that the same turns to a printing position corresponding to the selected key switch; and wherein each coupling means includes a first coupling member connected with the respective printing wheel for movement between said printing positions, a second coupling member disengageably coupled with said first coupling member and moved by said cam follower means, and arresting means operated by said electromagnetic means to block movement of said first coupling member in selected digital positions so that said second coupling member is disengaged from said first blocked coupling member while moving with said cam follower means.

21. Key controlled setting apparatus for printing wheels, comprising, in combination, a series of printing wheels, each having a set of types, and being turnable between a set of printing positions; drive means including a drive shaft supporting said printing wheels for rotation, a motor, and a Geneva transmission connecting said motor with said drive shaft so that the same is step-wise turned between digital positions; a series of coupling means for connecting said drive shaft with said printing wheels, re-

spectively so that said drive shaft transmits stepwise movement to said coupling means and printing wheels so that the same turn between said printing positions; a set of cam means rotated by said drive means; a control circuit including a series of electromagnetic means for operating said coupling means, respectively, a series of sets of key switches, and a set of interrogation switches sequentially actuated by said cam means, respectively, during one revolution of said set of cam means and connected with said key switches, respectively, of said sets of key switches so that when a selected key switch of any set of key switches is actuated, the respective correlated electromagnetic means operates the respective correlated coupling means upon actuation of the respective interrogation switch to couple said drive means with the respective printing wheel so that the same turns to a printing position corresponding to the selected key switch; and a printing cylinder having a cavity in which said motor, Geneva mechanism, drive shaft, printing wheels, coupling means, cam means, and electromagnetic means are located.

22. Key controlled setting apparatus as claimed in claim 21 wherein said control circuit is connected with said motor, and includes a start switch for starting said motor, relay means including a holding contact for said motor, and another switch operable to disconnect said relay means; and wherein said drive shaft means has a projection for operating said other switch at the end of one revolution.

23. Key controlled setting apparatus as claimed in claim 22 including arresting means biased for arresting said printing wheels in said printing positions, respectively, in which said types are aligned in axial rows; wherein said control circuit includes another electromagnet for moving said arresting means to a releasing position, and being energized by operation of said start switch, and being de-energized by said other switch so that said arresting means arrests said printing wheels.

24. Key controlled setting apparatus as claimed in claim 21 wherein each coupling means includes a biased coupling pawl mounted on the respective printing wheel and a set of coupling teeth on said drive shaft for coupling said drive shaft with said printing wheels in said printing positions of the same, respectively.

25. Key controlled setting apparatus as claimed in claim 24 wherein each electromagnetic means includes an electromagnetic and a control lever operated by said electromagnet to move said biased coupling pawl to a position releasing said coupling teeth of said drive shaft; comprising a series of contacts connected with said electromagnets, respectively, and mounted on said printing cylinder; a fixed support; and a contact member mounted on said fixed support for movement between a retracted position and an operative position, and including a series of contacts respectively engaging said contacts on said printing cylinder in said operative position for simultaneously energizing all said electromagnetic means in an initial position of said printing cylinder.
